ENCLOSING CASING FOR ELECTRICAL
CONTROL DEVICES

Herman J. Koch, Wauwataosa, and Anthony A. Kraus, Milwaukee, Wis., assignors to Cutler-Hammer, Inc., Milwaukee, Wis., a corporation of Delaware

Application November 6, 1941, Serial No. 418,054

9 Claims. (Cl. 220—55)

This invention relates to improvements in enclosing casings for electrical control devices. The invention relates more particularly to improvements in devices for releasably latching or fastening the covers of such casings in closed position.

A primary object of the invention is to provide an improved and simplified manually operable latching device for clamping a casing cover in closed position—the elements of the latch being concealed.

Another object is to provide novel means for effecting manually controlled movement of the latch to and insuring retention thereof in either latching or unlatching position.

Another object is to provide novel and simple means for cooperation with the latching device or devices for rendering the enclosing casing substantially dust-tight.

Another object is to provide a novel form of 20 casing and cover wherein a plurality of latching devices may be utilized as the sole means for retaining the cover in assembled and closed position relatively to the casing.

Another object is to provide a novel arrangement of parts whereby the manual operating knobs of the latching devices are at all times readily accessible exteriorly of the walls of the casing.

Another and more specific object is to provide for complete removal of the cover or door of an enclosing casing of an electrical control device, without the use of tools.

Another object is to generally improve the structural details and operating characteristics of cover latching devices of the aforementioned character.

Another object is to provide a novel form of casing and cover whereby the casings may be stacked or arranged close together (as in a cubicle panel or control center) without interfering with assembly or removal of the casing covers.

Another object is to provide casings and covers of neat and attractive appearance.

Other objects and advantages of the invention will hereinafter appear.

The accompanying drawing illustrates certain embodiments of the invention which will now be described, it being understood that the embodiments illustrated are susceptible of modification in respect of certain structural details thereof without departing from the invention as defined by the appended claims.

In the drawing,

5 Figure 1 is a fragmentary view of a metal enclosing casing and cover having our improved cover latching or attaching device associated therewith—the casing and cover members being shown in section and the manually operable latch being shown in side elevation.

Fig. 2 is a fragmentary view similar to Fig. 1, but with most of the elements of the latching device also shown in section.

Fig. 3 is a fragmentary sectional view, on the line 3—3 of Fig. 1.

Fig. 4 is a front elevational view, on a greatly reduced scale, of a sheet metal housing and cover forming an enclosing casing for an electrical control device of any suitable form (not shown), and illustrating use of four of our improved latching devices to clamp the cover in closed position with respect to the housing, an end portion of the cover being broken away to illustrate the relationship of the peripheral gasket with respect to the housing and cover.

Fig. 5 is a front elevational view of a modification wherein the housing has a flanged cover hinged thereto, and a single latching device, of the character herein disclosed, is utilized to effect retention of the cover in closed position, a portion of the cover being broken away to illustrate the slightly different arrangement of the peripheral gasket.

30 Fig. 6 is a perspective view of the latch element shown in Figs. 1 to 3, and

Fig. 7 is a perspective view of the metal washer which is rotatable with the shank associated with the manual operating knob, and against which washer one end of the coiled compression spring is adapted to bear.

Referring first to Figs. 1 to 4, 6 and 7, the numeral 10 designates generally the peripheral wall of a sheet metal housing of rectangular contour; or the rectangular front end portion of one unit of a cubicle or electrical control center of known form. In accordance with our invention there is preferably rigidly attached to each side and end wall of the housing 10, as by spot-welding, the vertical portion 11^a of a sheet metal strip member of approximately Z-form in transverse cross section, whereby flange portions 11^b extend inwardly in a common plane at right angles to the peripheral wall 10 and offset inwardly a predetermined distance from the outer edge 10^a of said peripheral wall.

Each of said members of Z-form includes a portion 11^c extending a predetermined distance toward, but short of, the edge 10^a of the peripheral wall 10 in substantially parallel rela-

tionship to the latter, thus providing a peripheral channel which is adapted to receive with a snug fit the lower edge portion of a gasket 12, which may consist of a single strip or length of material extending completely around the inner surface of peripheral wall 10, as best illustrated in Fig. 4. The upper edge of gasket 12 is preferably located inwardly of the edge 10a of wall 10 but forwardly of the edges of portions 11c of said members of Z-form.

When it is desired to provide a substantially dust-tight fit or connection between the housing member and the cover member 13, the gasket 12 may be composed of felt or other suitable fibrous material. On the other hand, where the connection between the housing and cover 13 is to be made water-tight, the gasket 12 will preferably be composed of resilient or live rubber or a compressible rubber-like material.

As shown in Fig. 4, the flat sheet metal cover member 13 is adapted to be freely inserted within the peripheral wall 10 of the housing; and as shown the same is provided adjacent to each edge of the longer sides thereof with a pair of substantially circular openings 13a (Fig. 2). The openings 13a are adapted to provide rotating clearance for the portion 14a of a stud or shank of hexagonal (or other polygonal) form in transverse cross section. Portion 14a is provided adjacent to its upper end with a reduced portion or neck 14b (Fig. 2) which provides for positive anchorage thereof within a manually operable knob 15. In practice we prefer to form the knob 15 of a zinc base metal alloy which is die cast to the form illustrated about the upper end of portion 14a of said shank, thus rigidly uniting said parts.

Knob 15 comprises an upper finger grip portion 15a of the contour best illustrated in Figs. 1, 4 and 5, which merges into a lower portion 15b of substantially circular contour. Portion 15b is provided in its lower surface with a substantially circular recess 15c (Fig. 2) which is adapted to accommodate a portion of the thickness of a washer 16, which is preferably composed or formed of felt, to provide a dust-tight gasket surrounding the respectively associated opening 13a (Fig. 2) upon normal compression of washer 16 between the lower end of knob 15 and the upper surface of cover member 13. In practice washer 16 is made of greater thickness at the central portion adjacent to opening 13a, as shown at 16a in Figs. 1 and 2; and the same is also preferably provided with a central opening 16b (Fig. 2) to afford rotatable clearance for shank portion 14a. If it is desired to provide a water-tight connection of the parts associated with the opening or openings 13a, the washers 16 may be composed of live or resilient rubber or a rubber-like material.

The portion 14a of the shank at the inner surface of cover member 13 is surrounded by a washer 17, preferably formed of steel or other suitable metal, having a central opening 17a (Fig. 2) affording rotatable clearance for said shank portion. A steel washer 18 underlies washer 17, the washer 18 having a hexagonal opening 18a (Fig. 7) to provide a close sliding but non-rotatable fit with respect to shank portion 14a. Said shank is provided with a lower end portion of reduced diameter which is threaded as shown at 14c; and the extreme lower end portion of said shank is still further reduced, as shown at 14d. Portion 14d is provided with a peripheral groove 75

14e, which is adapted to receive a horseshoe-shaped washer 19, preferably formed of steel.

Prior to attachment of washer 19 a coiled compression spring 20 is telescoped onto the shank 5 portions 14c, 14a, with one end thereof abutting washer 18. Thereupon the latching or clamping member 21 is threaded onto the shank portion 14c. Member 21 preferably comprises a metal die casting of the form illustrated, the upper end 10 21a of the body portion thereof being preferably of approximately diamond-shape and having its outer surfaces flaring in a downward direction until portions thereof meet or merge with the substantially centrally located bottom portion 21b. 15 Portion 21a is provided with an upwardly opening recess 21c of substantial depth, against the bottom wall of which recess the other end of spring 20 is adapted to abut. Member 21 is provided with a tapped opening 21d (Fig. 2) which is centrally aligned with the bottom wall of said recess 21c, said tapped opening being adapted to accommodate the threaded shank portion 14c to provide for adjustable relative movement between said parts. After member 21 has been threaded onto 20 shank portion 14c to a sufficient degree, the aforementioned washer 19 is attached, the latter acting to positively limit the degree of downward displacement of member 21 relatively to the shank. 25 30 The two side surfaces 21e and 21f of member 21 are arranged at a predetermined angle to each other, whereby the same are selectively adapted to engage the vertical portion 22a of an angle iron, the horizontal portion 22b of which is rigidly attached to the lower surface of cover member 13, as by spot welding. Said angle iron may be of just sufficient length for proper cooperation with one pair of the surfaces 21e and 21f of a member 21; but where two or more of the latch 35 members 21 are associated with a side of cover plate 13 (as in Fig. 4) we prefer to employ a single angle iron of a length to cooperate with the surfaces of all of the latch members associated with said side or edge portion of the cover member. 40 45

Each member 21 is provided with an integral laterally extending horizontal lug 21g offset downwardly from the upper end thereof, said lug being preferably of the contour best illustrated in 50 Figs. 3 and 6, wherein the convergent sides 21h and 21i merge with the straight side 21j—which side 21j is adapted to abut the vertical portion 11a of the aforementioned Z-bar upon clockwise rotation of latch member 21 with respect to the casing or housing 10 (see Fig. 3).

Thus, with reference to Figs. 1 to 4, it may be assumed that prior to insertion of cover 13 into the open end of the housing, as represented by peripheral wall 10, the knobs 15a have been 60 rotated counterclockwise to effect movement of the latch members 21 inwardly of their respectively associated shanks (as indicated in dotted lines at 21x in Fig. 2) to such an extent that the lugs 21g thereof are located in a plane or 65 planes below the common plane of the portions 11b of the Z-bars, it being understood that during such counterclockwise movement of the knobs the latch members will likewise each have been moved counterclockwise to the extreme position thereof indicated in dotted lines at 21x in Fig. 3. Also, as will be understood, in such extreme counterclockwise position of each latch member 21 the lug 21g thereof will be so positioned as to 70 permit the same to clear its associated Z-bar as cover 13 is manually moved into engagement.

with gasket 12. Thereafter upon clockwise rotation of each knob 15^a its associated latch member 21 will first be moved clockwise to the full line position thereof shown in Fig. 3, wherein it underlies the horizontal portion 11^b of its associated Z-bar; such initial clockwise movement of latch member 21 being insured—in part by the fact that shank portion 14^c, washer 18 and spring 20 will tend to rotate clockwise as a unit, thus having a biasing effect upon the latch member 21 to also tend to effect clockwise rotation of the latter, and in part by the normal tendency of latch member 21 to rotate in the same direction as the threaded portion 14^c of the shank.

As each latch member reaches its extreme clockwise position (shown in full lines in Fig. 3) further clockwise rotation of the manual operating knob 15^a will effect upward movement of lug 21^c into engagement with the portion 11^b of the Z-bar, and thereafter the relative movement between the shank portion 14^c and member 21 results in further compression of washer 16 against the outer surface of cover member 13 by bottom portion 15^b of the knob and simultaneous pressure of the inner surface of cover member 13 against the peripheral gasket 12. The degree of pressure with which the inner surface of cover member 13 is engaged with gasket 12 will, of course, depend upon the degree of manual rotating pressure finally applied to the several knobs 15^a; it being understood that the degree of dust-tightness of the gasketed parts may thus be controlled at will.

When it is desired to remove the cover member 13 it is only necessary to reverse the afore-described operation; the knobs 15^a when first rotated counterclockwise permitting outward movement of cover member 13 to relieve the pressure of the latter against the gasket 12, and thereafter the members 21 are moved bodily inwardly until the lugs 21^c thereof clear the portions 11^b of the Z-bars. When such clearance is provided the latch members 21 are free respectively to rotate in a counterclockwise direction to the aforementioned extreme position indicated in dotted lines at 21^x in Fig. 3, in which position the lug 21^c will clear the Z-bar. When all of the latch members 21 have been so positioned cover member 13 may be readily removed manually, one or more of the knobs 15^a being used to pull or tilt the same outwardly from the peripheral wall, if necessary.

As will be apparent from Figs. 1 and 2, the arrangement is such that the manually operable portions 15^a of the knobs are at all times accessible exteriorly of the open end of the casing.

It is to be understood that in Fig. 4 we have illustrated use of the cover 13 for a casing or housing for a control device of the automatically operable type, it being obvious that, if desired, the cover 13 may have attached thereto any suitable handle, pushbutton, or other operating member having a cooperative or interlocking relationship with a part of the switch or other control device enclosed within the housing.

In the modification of Fig. 5, the housing includes a peripheral wall designated 23, the opposite side and end portions of said peripheral wall having Z-bars attached thereto, as indicated at 24 and 25. The gasket 26 which fits into the upwardly opening peripheral pocket formed by said Z-bars preferably extends forwardly beyond the front edge portion 23^a of said peripheral

wall, inasmuch as the cover member 27 at all times overlies said front edge portion 23^a, and said cover member has a downwardly extending peripheral flange 27^a which surrounds said peripheral wall. Cover 27 is hinged at one side thereof to the peripheral wall 23 of the housing, as shown at 28 and 29; and said cover 27 is provided adjacent to the opposite side thereof with a single one of our improved latching devices, the knob portions of which are shown at 15^a and 15^b. The latching element of the character aforescribed is adapted for cooperation with the horizontal portion of the adjacent Z-bar, and said single latching device is adapted to operate in the manner aforescribed to effect releasable retention of cover 27 in closed position, the other elements of the latching device being adapted to function as aforescribed to provide the desired degree of pressure of cover 27 against the dust-tight gasket 26. As in the device of Figs. 1 to 4, the latching device of Fig. 5 is moved to clamping position and thereafter tightened as an incident to clockwise movement of the knob 15^a, whereas the latch is loosened and the cover 27 released as an incident to counterclockwise movement of said knob.

Although the cover 13 of Fig. 4 is adapted for complete removal from the housing, it will be obvious to those skilled in the art that the same might be hinged at one side (say, the left-hand side) to the inner surface of one side wall of the housing—the opposite side of the cover being provided with one (as shown in Fig. 5) or more latching devices of the aforescribed character to effect releasable closing and clamping of the cover in substantially the same manner as that heretofore mentioned.

As will be apparent from Figs. 4 and 5, our improved latching means has all portions thereof, except the operating knob, concealed, and thus the same provides a finished housing or casing and cover of neat and attractive appearance.

We claim:

1. In combination, a sheet metal switch casing having an open front end, a metal flange extending inwardly from the walls of said casing throughout the periphery of the latter and offset inwardly from said open end, a gasket seated upon said flange throughout the length of the latter, a sheet metal cover member adapted to overlie said gasket and to seat thereagainst, said cover member having at least one substantially circular opening formed therein adjacent to the periphery thereof but spaced inwardly therefrom to clear said flange, a device for securing said cover in closed position, said device including a manually operable knob forming the sole element thereof exposed at the outer surface of said cover member, a metal shank extending inwardly from said knob through said cover opening, said shank having a threaded inner end, a latch member having threaded engagement with said shank, said latch member being initially positioned a predetermined distance inwardly of said cover member and having an integral lug arranged at a rotary angle to permit passage thereof inwardly beyond the plane of said flange, a metal washer slidably but non-rotatably carried by said shank at the inner surface of said cover member, a coiled spring interposed under compression between said washer and said latch member to provide a frictional rotary driving connection between said shank and said latch member, the arrangement

being such that upon clockwise rotation of said knob said lug is moved clockwise to underlie said flange and thereafter said shank and said latch member are moved axially relatively to each other to effect engagement of said lug with the inner surface of said flange and simultaneous compressing engagement of said cover member with said gasket, and said cover and said casing having cooperating elements at the side thereof opposite to said securing device to assist in retaining said cover in closed position.

2. In combination, a sheet metal switch casing having an open front end, a metal flange extending inwardly from the walls of said casing throughout the periphery of the latter and offset inwardly from said open end, a gasket seated upon said flange throughout the length of the latter, a sheet metal cover member adapted to overlie said gasket and to seat thereagainst, said cover member having at least one substantially circular opening formed therein adjacent to the periphery thereof but spaced inwardly therefrom to clear said flange, a device for securing said cover in closed position, said device including a manually operable knob forming the sole element thereof exposed at the outer surface of said cover member, a metal shank extending inwardly from said knob through said cover opening, said shank having a threaded inner end, a latch member having threaded engagement with said shank, said latch member being initially positioned a predetermined distance inwardly of said cover member and having an integral lug arranged at a rotary angle to permit passage thereof inwardly beyond the plane of said flange, said threaded inner end of the shank having an integral extension of reduced diameter, said extension having a peripheral groove formed therein, a notched washer adapted to fit within said groove, said washer acting to positively limit the degree of inward movement of said latch member, said latch member having axially extending surfaces arranged at an angle to each other, said cover member having an angle iron rigidly attached to the inner surface thereof and cooperating with said surfaces of the latch member to positively limit rotary movement of the latter in each direction, a metal washer slidably but non-rotatably carried by said shank at the inner surface of said cover member, a coiled spring interposed under compression between said last mentioned washer and said latch member to provide a frictional rotary driving connection between said shank and said latch member, the arrangement being such that upon clockwise rotation of said knob said lug is moved clockwise to underlie said flange and thereafter said shank and said latch member are moved axially relatively to each other to effect engagement of said lug with the inner surface of said flange and simultaneous compressing engagement of said cover member with said gasket, and said cover and said casing having cooperating elements at the side thereof opposite to said securing device to assist in retaining said cover in closed position.

3. In combination, a metal switch casing having an open front end, means providing a peripheral shoulder offset inwardly from said front end, a cover member freely insertable into said opening and adapted to overlie said shoulder, said cover member having a multiplicity of substantially circular openings formed therein adjacent to the peripheral edge thereof but spaced inwardly therefrom to clear said shoulder, a

corresponding number of members for jointly securing said cover to said casing, said members having manually operable knobs forming the sole elements exposed at the front face of said cover

- 5 member, a shank extending inwardly from each knob through one of said openings, said shank having a threaded inner end, a latch member having threaded engagement with said shank, a washer positively rotatable with said shank, a coiled spring interposed under compression between said washer and said latch member, and each latch member being initially positioned a predetermined distance inwardly of said cover member and having a lug arranged at a rotary angle to clear said shoulder, the arrangement being such that upon clockwise rotation of said knob said lug is frictionally moved clockwise, jointly with said shank, said washer and said spring, to underlie said shoulder and thereafter
- 10 said shank and said latch member are moved axially relatively to each other to effect clamping movement of said cover member and said lug toward the outer and inner surfaces of said shoulder.
- 15 4. In combination, a metal switch casing having an open front end, means providing a peripheral shoulder offset inwardly from said front end, a metal cover member freely insertable into said opening and adapted to overlie said shoulder, said cover member having a multiplicity of substantially circular openings formed therein adjacent to the peripheral edge thereof but spaced inwardly therefrom to clear said shoulder, a corresponding number of members for jointly
- 20 securing said cover to said casing, said members having manually operable knobs forming the sole elements exposed at the front face of said cover member, a shank extending inwardly from each knob through one of said openings, said
- 25 shank having a threaded inner end, a latch member having threaded engagement with said shank, a washer positively rotatable with said shank, a coiled spring interposed under compression between said washer and said latch member, each latch member being initially positioned a predetermined distance inwardly of said cover member and having a lug arranged at a rotary angle to clear said shoulder, the arrangement being such that upon clockwise rotation of said knob said lug is frictionally moved clockwise, jointly with said shank, said washer and said spring, to underlie said shoulder and thereafter
- 30 said shank and said latch member are moved axially relatively to each other to effect clamping movement of said cover member and said lug toward the outer and inner surfaces of said shoulder, and means comprising a gasket positioned upon the outer surface of said shoulder and against which said inserted cover member is drawn, for the purpose set forth.
- 35 5. As an article of manufacture, a metal cover member for electric switch enclosing casings and the like, said cover member having a plurality of relatively small substantially circular openings formed therein adjacent to peripheral edge portions thereof, a corresponding number of manually rotatable knobs having shanks extending inwardly through the respective openings, said shanks each having a portion
- 40 of polygonal form in transverse cross section adjacent to its respective knob and a screw-threaded inner end portion, a pair of washers arranged on opposite faces of said cover member and having openings to provide rotary clearance
- 45 for said shank, at least one of said washers be-

ing non-metallic, a metal washer underlying the inner washer aforementioned, said metal washer having a polygonal opening to provide for rotation thereof by said shank portion first mentioned, a coiled spring surrounding said shank and having its upper end engaged under compression at all times with said last mentioned washer, a metal latch member having an upwardly opening pocket formed therein to accommodate the lower end portion of said spring, 10 the bottom wall of said pocket having a tapped opening formed therein for cooperation with said threaded shank portion, an angle bar rigidly secured to the inner surface of said cover member, said latch member having angularly related sides cooperable with said bar to limit rotation of the former in each direction, a lug formed integrally with said latch member and extending therefrom in a horizontal plane in opposed relation to said angularly related sides, 15 said latch member being initially spaced inwardly a predetermined distance from said cover member and adapted in its extreme counterclockwise position to provide for retracted positioning of said lug, the arrangement being such that upon clockwise rotation of said knob said latch is first rotated to its extreme clockwise position to effect projection of said lug and thereafter said latch member is drawn axially of said shank to provide for clamping engagement of 20 said lug with an overhanging shoulder or the like.

6. In an enclosing casing for electrical control devices and the like, in combination, a metal housing member having an opening and peripheral walls surrounding said opening, a sheet metal bar of approximately Z-form in transverse cross section rigidly and permanently secured to each of said peripheral walls in inwardly offset relation to the forward ends of the latter in a manner to provide a forwardly opening peripheral pocket, a gasket positioned within said peripheral pocket and projecting forwardly of the latter, a flat metal cover member freely insertable into said opening in closely adjacent relationship to the peripheral walls of the latter and adapted to overlie said gasket, a plurality of manually operable latch members carried by said cover member, each of said latch members comprising a manually operable knob forming the sole element thereof exposed at the forward face of said cover member, said knob having a shank and said cover member having an opening to rotatably receive said shank, a composition washer interposed between said knob and the forward face of said cover member to form with said shank a substantially dust-tight closure for said cover opening, a latch element having a pocket formed therein and a tapped opening formed in the bottom wall of said pocket, said shank having a threaded portion adapted to cooperatively engage said tapped opening, a coiled spring interposed under compression at all times between said bottom wall of the pocket and the inner surface of said cover member, said cover member having an angle bar welded to the inner surface thereof, said latch element having angularly arranged surfaces cooperable with said angle bar to limit the degree of rotation of the former in each direction, and said latch element having a lug formed integrally with one side thereof, the arrangement being such that upon counterclockwise movement of said knob said lug is moved inwardly out of clamping engagement and then rotarily to a

position to clear the lower surface of the horizontal portion of said Z-bar and said latch element is thereafter moved bodily inwardly of said shank, so that upon subsequent clockwise movement of said knob said lug is first moved into underlying relation to said lower surface of the horizontal portion of said Z-bar and thereafter into engagement with the latter, whereupon said shank moves inwardly relatively to said latch element to effect movement of said cover member into clamping engagement with said peripheral gasket.

7. As an article of manufacture, a latching device adapted to be attached to the cover of an electrical switch housing or the like, said device comprising a manually rotatable knob forming the sole element thereof exposed upon the outer surface of the cover, a shank rigidly attached to said knob and projecting inwardly through an opening in the cover, the portion of said shank adjacent to said knob being of polygonal form in transverse cross section, a metal washer non-rotatably fitted onto said polygonal portion of the shank, a coiled spring the upper end of which is engaged under compression at all times with said washer, a latch member having an upwardly opening recess to accommodate the lower end of said spring, the bottom wall of said recess having a tapped opening formed therein, the lower end of said shank being threaded for cooperation with said tapped recess, said latch member having angularly related sides for cooperation with a suitable stop upon the inner surface of the cover member to limit the angular degree of rotation of said latch member, said spring cooperating with said washer and said latch member to provide a relatively strong frictional rotary bias of said latch member between each of the extreme angular positions of the latter upon rotation of said shank in corresponding directions, said latch member having an integral laterally extending lug adapted for movement into and out of underlying relation to a shoulder formed on the switch housing, for the purpose set forth.

8. In an enclosing casing for electrical control devices and the like, in combination, a vertically mounted sheet metal housing including an open front end portion of rectangular contour, the opposed side and end walls of said front end portion having flanges extending inwardly therefrom in a common plane at right angles thereto and offset inwardly a substantial distance from the front edges thereof, a flat, punched sheet metal cover member of a size and contour closely approximating those of said open front, said cover member being adapted for assembly by seating the lower edge thereof against the lower end wall of said open front whereupon said cover member may be swung inwardly toward said flanges, said cover member having a plurality of substantially circular openings formed therein adjacent to the opposite vertical edges thereof but spaced inwardly from the latter to clear the respective side wall flanges, a corresponding number of members for jointly securing said cover member to said housing, said members having manually operable knobs forming the sole elements exposed at the front face of said cover member, a shank extending inwardly from each knob through one of said openings, said shank having a threaded inner end, a latch member having threaded engagement with said shank, each latch member being initially positioned a predetermined distance inwardly of said cover

member and having a lug arranged at a rotary angle to clear the adjacent flange, a washer slidably but non-rotatably carried by each shank, a coiled spring interposed under compression between said washer and said latch member, whereby upon clockwise rotation of each knob the associated latch lug is moved clockwise to underlie the adjacent flange, and whereby upon further clockwise movement of said knobs the associated shanks and latch members are moved axially relatively to each other to effect movement of said cover member toward the respective flanges.

9. In an enclosing casing for electrical control devices and the like, in combination, a vertically mounted sheet metal housing including an open front end portion of rectangular contour, the opposed side and end walls of said front end portion having flanges extending inwardly therefrom in a common plane at right angles thereto and offset inwardly a substantial distance from the front edges thereof, a flat, punched sheet metal cover member of a size and contour closely approximating those of said open front, said cover member being adapted for assembly by seating the lower edge thereof against the lower end wall of said open front whereupon said cover member may be swung inwardly toward said flanges, said cover member having a plurality of substantially circular openings formed therein adjacent to the opposite vertical edges thereof but spaced inwardly from the latter to clear the respective side wall flanges, a corresponding num-

ber of members for jointly securing said cover member to said housing, said members having manually operable knobs forming the sole elements exposed at the front face of said cover member, a shank extending inwardly from each knob through one of said openings, said shank having a threaded inner end, a latch member having threaded engagement with said shank, each latch member being initially positioned a predetermined distance inwardly of said cover member and having a lug arranged at a rotary angle to clear the adjacent flange, a washer slidably but non-rotatably carried by each shank, a coiled spring interposed under compression between said washer and said latch member, whereby upon clockwise rotation of each knob the associated latch lug is moved clockwise to underlie the adjacent flange, whereby upon further clockwise movement of said knobs the associated shanks and latch members are moved axially relatively to each other to effect movement of said cover member toward the respective flanges, felt washers surrounding the respective shanks and interposed between said knobs and the outer surface of said cover member, and a felt gasket seated upon the respective flanges, whereby said enclosing casing is rendered substantially dust-tight, the arrangement of the aforementioned parts being such that the manually engageable portions of said knobs are at all times positioned forwardly of the front edge portions of said housing.

HERMAN J. KOCH.
